UNITED STATES PATENT OFFICE.

WALTER L. CLARK, OF NEW YORK, N. Y., AND WILFORD J. HAWKINS, OF MONTCLAIR, NEW JERSEY, ASSIGNORS TO AMERICAN DAN BOTTLE SEAL CORPORATION, OF DOVER, DELAWARE, A CORPORATION OF DELAWARE.

VESSEL SEAL.

Application filed April 1, 1922. Serial No. 548,726.

To all whom it may concern:

Be it known that we, WALTER L. CLARK, a citizen of the United States, residing in the city, county, and State of New York, and WILFORD J. HAWKINS, a citizen of the United States, residing at Montclair, in the county of Essex and State of New Jersey, have invented certain new and useful Improvements in Vessel Seals, of which the following is a specification.

This invention relates to bottle or vessel seals and has for its object to provide a vessel seal of improved construction for use on vessels of various kinds for still or carbonated liquids.

More specifically, our invention contemplates an improved vessel closure or cap which may be economically constructed, readily applied, which will make an effective seal for liquids under high pressure but which nevertheless may be readily removed from the vessel without the use of a special tool.

One of the objects of the present invention is to obviate the use of cork inserts or similar devices in caps for bottles containing liquids under pressure.

Another object of invention is to provide a vessel closure of such construction that the pressure exerted by the contained liquid against the cap will render the seal more effective.

More specifically stated, the object of our invention is to provide an improved seal for a bottle having the neck thereof provided with a bead, said seal consisting of a malleable metal cap having the lower edge of its flange swaged and drawn into rigid engagement with the outer wall of said bead and bottle neck in such a way that the portion in engagement with the bottle neck constitutes a continuous anchoring skirt which is hardened into engagement with the bottle neck by conducting the swaging action on all parts of the skirt simultaneously.

By the term "drawn" in the above statement, is meant the effect of pulling or drawing down the metal produced by the swaging action applied to the skirt over an area extending downwardly from about two-thirds of the way down on the bead.

The drawings show a preferred embodiment of our invention.

Figure 1 is an axial section of a bottle cap

adapted to be applied to a bottle according to the principles of our invention;

Figure 2 is an axial section of the upper end of a bottle to which the cap has been applied and after the completion of the sealing operation;

Figure 3 is a side elevation of the same;

Figure 4 is an axial section similar to Figure 2, according to which a layer is interposed between the outer surface of the bottle and the inner surface of the cap;

Figure 5 is an axial section of another embodiment according to which the bottle cap is provided with a cork insert;

Figure 6 is an axial section of a modified construction according to which the vessel is provided with a protective cap.

Heretofore, the most usual form of bottle seal in common use has been the so-called "Crown cork and seal." In this closure, a flat washer of cork is used as a gasket which after being pressed upon the mouth of the bottle or vessel, is held securely in position to maintain a hermetic seal by means of a metallic cap of relatively stiff metal. These caps are usually stamped from sheet steel and plated with tin. There are certain disadvantages to be met with in the use of hardened metal caps as compared to soft metal caps. Thus, the hardened metal caps require special tools for removing the caps and after they have been removed they can be used again, thus enabling the dishonest refilling of a bottle. Soft metal caps on the other hand, may be torn off by the fingers alone and inasmuch as they are destroyed by their removal, refilling of the bottle is prevented. Furthermore, soft metal caps require less weight of metal, cost less, and require very much less power (in the case of applicants' cap) to apply them than do the hardened metal caps.

Referring more particularly to the drawings, in the embodiment of our invention shown in Figures 1, 2 and 3, the bottle cap comprises a flat top wall 1, a lateral flange which merges into the top wall, preferably, by a rounded top corner 3 and a pair of oppositely disposed depending lobes or finger grips 4. The bottle shown in the drawings, a standard type in the United States is provided with a rounded protuberant bead 8 extending around the mouth thereof and with a constricted area 9 which constitutes

a neck immediately below said bead. In applying a cap to a bottle, said cap is caused to assume its final form as it is being secured in position on the bottle. For this purpose, the malleable metal flange is made of such depth as will allow sufficient metal to form an anchoring skirt 6 having rigid contact with the constricted area 9 or outer wall of the neck of said bottle. During the swaging action which imparts the final form to the cap, the circumferential portion of the flange which is to be condensed to form the anchoring skirt 6 is operated upon at all points simultaneously by the steel swaging jaws and at the end of their inward movements said jaws constitute substantially a continuous steel band. The effect of this operation is to greatly increase the hardening effects upon the metal to a degree which is impossible to obtain with spinning, crimping or soft rubber squeezing operations. It is to be noted also that the anchoring skirt 6 which is condensed and hardened in the manner above noted is seated around the neck 9 of the bottle and is thus made to rigidly engage the outer surface thereof around its smallest diameter and underneath the protuberant bead.

That portion of the flange which is compressed under the bead or shoulder constitutes a hardened anchoring band or skirt which is substantially inelastic and rigidly engages the outer wall of the bottle neck and under surface of the bead.

By this method of closure, it will be noted that the interior pressure denoted by the arrows P. P. P. sets up resisting forces R. R. acting over the surface A—B, see Figure 2. It is obvious that the greater the value of the pressure P, the greater will be the magnitude of the resisting pressures R. R.

In this method of manufacturing bottle seals, thin aluminum sheets from .006" to .008" thick may be used for forming the bottle closure, and, if so desired, it may be drawn into the form of a preliminarily shaped cap, then applied to the mouth of the bottle and thereafter compressed to conform with the outer contour of the bottle or vessel mouth.

In the case of the "Crown cork and seal" and other similar devices deriving their seal from a cork or gasket compressed against the top of the mouth of the vessel or bottle, a heavy pressure upon the seal and the bottle is necessary in order to provide a tight seal of permanent character. This heavy pressure necessary to compress the cork or gasket ranges above 500 lbs. total pressure and may go as high as 1100 or 1200 lbs. which the bottle must support in the sealing process. The use of such heavy pressure causes a relatively large bottle breakage. It is to be noted that in our invention no such pres-

sure is required since no gasket or cork is necessarily used, the seal being on the under side of the bead and along the periphery of the bead at the mouth of the bottle or vessel. The absence of cork in our method of closure makes such pressure unnecessary and reduces the percentage of bottle breakage under the sealing machine to practically nothing. This feature is a marked improvement over the other methods now and previously in use.

Our bottle seal is an improvement over the "Crown cork and seal" and other similar devices now in common use, inasmuch as it dispenses with the need for the cork or gasket, and inasmuch as it seals more and more tightly as the interior pressure in the bottle or vessel increases.

When crimping jaws are employed for securing the flange of a soft metal cap below the bead on a vessel, the soft metal is left free to bulge outwardly in the spaces between the crimping jaws. The condensing pressure is therefore not continuously applied so that the desired degree of hardness is not obtained. Spinning rolls on the other hand, when they travel around the flange of a soft metal cap, compress it at only one or two points at any given instant, the metal being freed from pressure at all other points. We are aware that soft rubber rings have been used for applying pressure on all parts of a soft metal flange at the same time but such a device is not capable of imparting any considerable hardening to the anchoring skirt of a soft metal cap.

If it is desired to still further increase the tightness of this seal, on account of slight roughnesses in the exterior of the bottle mouth, we employ the embodiment shown in Figures 4 and 5, in which a gasket forming material such as plastic gum, wax, balsam, gelatin, or other suitable material may be used for coating either the exterior contour of the bottle or vessel mouth or the interior of the skirt of the bottle seal, or for that matter the entire interior of the seal if so desired.

In the particular embodiment shown in Figure 4, the cap is applied to the vessel with its flat top wall 5 in direct contact with said vessel, the rounded upper corner 7 being pressed into snugly fitting engagement with the rounded bead 8 of the bottle lip. In order to provide an interposed gasket or seal forming layer between the flange of the cap and the outside contour of the bottle neck, a layer 10 of gasket or seal forming material may be coated onto the inner wall of the cap or onto the exterior surface of the bottle prior to the cap applying operation.

It will be understood from the foregoing description that the flanged portion of the

cap or seal which is indicated between A and B on Figure 2 has sealing contact with the outer circumferential wall of the vessel. This area of sealing contact is under tension due to the internal pressure P P P which tends to draw the flanged portion of the cap or seal into more intimate contour relation to the bead extending around the mouth of the vessel.

10 In the above description we do not 50
bar ourselves from using a coated strip of metal in the manufacture of the bottle or vessel closures herein described. The function of such plastic material is to perfect 55
the seal between the metallic cap and the exterior of the mouth of the bottle or vessel in the way that a gasket is used.

We are aware that there are many substances which can and have been used for 20
the purpose of a plastic material or gasket forming material. We prefer a material which is odorless, tasteless, insoluble in contents of the bottle or vessel, and of melting point higher than any temperature to which 25
the bottle or vessel to be sealed will be subjected either in the course of bottling or in use thereafter.

In order that thin metal may be used for the closure described above, we have dis- 30
covered that by hardening the skirt of the cap by conducting the swaging action thereon at all points simultaneously, the strength 35
of metal is materially increased.

If so desired the bottle seal or cap may 35
be made of a relatively soft malleable form 40
of aluminum and provided with tabs or ears or lobes whereby the cap may be readily removed from the mouth of the bottle or vessel by grasping one of the lobes 4 be- 45
tween the thumb and forefinger and tearing circumferentially around the cap (see Figures 1, 3 and 4).

In contracting the diameter of the flared flange of the cap from its form shown in 45
Figure 1 down to its diameter as shown in

Figures 2, 3, 5, or 6, we have discovered that the metal may be compressed without crimps or folds and when thus condensed by the steel swaging jaws acting simultaneously at all points around the circumference of the anchoring skirt, a relatively thin gage of metal can be employed for retaining liquids under relatively high pressures.

It is to be noted that in our form of construction a cork seal or other gasket may 55
be used on the top of the bottle mouth if so desired, but that it is not necessary inasmuch as the sealing surface is really on the flank of the metal mouth as indicated between the points A and B of Figure 2. It 60
is also to be noted that by omitting the use of a cork or other gasket under the cap, liquids under high pressures may be sealed with a material saving in the cost of manufacture of bottle seals.

According to the embodiment of our invention shown in Figure 6, the form of the vessel is preferably modified somewhat in connection with a suitable protective housing or outer protecting cap. For this purpose in the present embodiment, the tapering portion 17 of the bottle is provided with a thread 18 upon which is threaded the cap 19 of a closed protecting cap 20 which completely houses the closure.

75 We claim:—

The combination with a bottle or vessel having a bead, of a malleable metal cap having the lower edge of its flange swaged and drawn into rigid engagement with the 80
outer wall of said bead and bottle neck, that portion in engagement with the bottle neck constituting a continuous anchoring skirt, said skirt being hardened by the said swaging thereof into engagement with the bottle neck, said swaging action being conducted simultaneously on all parts of the skirt.

75
